DISPLAY CARD AND SUPPORT

Bernard A. Einson, Yonkers, N. Y., assignor to
 Einson-Freeman Co., Inc., Long Island City,
 N. Y., a corporation of New York

Application June 4, 1932. Serial No. 615,350

3 Claims. (Cl. 211—157)

The present invention has relation to advertising or display devices and consists of a show card and a supporting easel therefor preferably integral therewith. Heretofore many types of 5 combined show cards with an easel have been proposed and the most common form in use, designed to stand rigidly in an upright or display position, is composed of a flat, usually nonfoldable card, with a folding or collapsible easel 10 pasted on the back of said card. A device of this kind to some extent gives the needed rigidity and support so that the device will stand upright on a counter or elsewhere to perform its 15 function as an advertising medium.

Various other types of devices have also been proposed wherein the complete display device is composed of a single sheet having portions folded so as to form the combined show card and easel, and one object of the present invention is 20 to produce an improved device of the kind which will give the highest degree of efficiency obtainable. Also the improved device is of such simple construction that it may be economically produced, packed, and shipped and furthermore, 25 due to its simplicity, the improved device may be easily set up into the operative or display position.

In carrying out the present invention the device is preferably composed of a single sheet 30 blank cut and scored so as to form a central or main body portion forming the show card or display and portions partly cut away from the main portion of the blank at the sides thereof provide an easel or support for the device.

The improved device in its normal or inoperative position is flat and may therefore be readily packed and shipped and the improved device as designed lends itself to be made of a single sheet which is substantially rectangular, square or 40 other shape with no extensions etc. which are detrimental against the economical production of the blanks.

The operation of setting up the improved device is extremely simple and when set up the 45 easel support provides a firm base for the device and said support is such in all cases with regard to the center of gravity, that the device is firmly supported against accidental toppling over. Furthermore with such a support, in conjunction 50 with the natural rigidity of the card portion a device of considerable area may be composed of comparatively light weight paper board, and furthermore due to its rigidity at all points the improved device is capable of supporting a comparatively heavy piece of merchandise.

The improved device will be hereinafter more fully described with several embodiments of the invention together with details of construction and the description will be given with reference to the accompanying drawing wherein—

Figure 1 is a plan view of a single sheet blank 60 of which the improved device is composed;

Figure 2 is an elevation showing the device from the back and as standing in the erected or operative position;

Figure 3 is a side elevation of the device shown 65 in its erected position;

Figure 4 is a plan view of a modified form of the device;

Figure 5 is a side elevation of the erected de- 70 vice composed of the blank illustrated in Figure 4;

Figure 6 illustrates a blank of which another modified form of device is composed;

Figure 7 is a side elevation of the erected de- 75 vice composed of the blank illustrated in Figure 6; and

Figure 8 is a detail fragmentary view of a leg or support of the improved device having a flanged re-inforcement.

In the embodiment of the invention as illustrated in Figures 1, 2 and 3, the improved device is composed of a single sheet blank A having a body or main portion 1. Side pieces or portions 2 partly cut away from the main portion 85 1 are connected to the main portion 1 on diagonal crease lines 3 and these portions 2 fold downwardly and inwardly on said crease lines 3 so that when folded the two portions converge. The side portions 2 are creased on the lines 4 90 whereon the free ends 2 extending beyond these crease lines are folded downwardly so that the portions 2 form legs or supports 5 crossing at the point 6 where notches 7 are provided to hold the creased portions 2 in place. A series 95 of notches 7 may be provided so as to obtain adjustability to permit the show card or body of the device to stand in different angular or tilted positions.

The upper edges 8 of the portions 2 are cut on 100 a slant so that in the preferred angular position of the display card these edges will rest evenly on a flat surface and together with the lower edge 9 of the card 1 provide an extended base whereby the device is maintained in a firm 105 position.

It will be noted that the easel or support formed by the folded and creased side pieces 2 provides an exceedingly rigid support which is held 110 against opening beyond the set position and

against closing due to the angular inclination of the double folded supporting legs 5 formed by the crease portions 2. This effect is obtained by the opposite diametrical folding of 5 said side pieces at a point adjacent to the connection of the said portions to the body. The improved easel or support operates on the same principle as a tripod for the support is at three different points, that is, at the two free edges 10 of the folded legs 5 and the bottom edge of the display card. As stated this support is firm even when the device is composed of comparatively light weight board and being of such a firm nature the support will readily carry 15 merchandise which might be placed on the display card within an opening 10 formed by cut away piece 11 which latter may be folded downwardly to rest on the legs 5 and thereby provide a platform on which the merchandise will rest. 20 Referring to Figures 4 and 5 in the example shown therein the same principles are involved as found in the previously described examples but with the modification that the side leg or prop portions 2 are folded on single crease 25 lines 12. The similarity of this blank A' to the blank A shown in Figure 1 is best shown by pointing out that the blank A' is substantially the same only it is inverted. Another difference is that the top of the card has a cut out portion 30 13 which is surmounted by the crown portion 14. In the example now referred to the ends of the legs or props 2 are oppositely notched at 15 so that the two legs will be held together in the converged position.

35 Figures 6 and 7 illustrate an embodiment of the invention which is practically the same as that shown in Figures 4 and 5 with the exception that in the blank A'' the cut out top portion is eliminated and legs or props 2 are 40 tapered, narrowing towards the bottom so as to stiffen the legs by graduation so that said legs are strengthened at their point of connection on the crease line 12. It is of course desirable that the supporting legs when comparatively long, should be stiffened and particularly 45 when comparatively light weight stock is used; therefore to give additional strength thereto the outer edge of the legs are provided with a flange 16 as shown in Figure 8.

50 The improved device has the essential differentiating characteristics over other one piece display and easel devices in that the improved device has the side legs or props partly cut from the main portion of the blank and arranged 55 so that they are united thereto on the crease lines 3, 4 or 12 which are diagonally disposed whereon the two legs will fold inwardly

so as to converge. When folded properly the natural tendency for these inwardly folding legs is to remain in the converged position and therefore the easel will to some extent, which may be sufficient in many or most instances, remain in the operative position without the necessity of engaging or locking the two ends together. In the unlocked position the two legs of the easel and the card form a perfect tripod and the set up easel will therefore stand in a firm set supporting position. This desired effect will be best produced with the embodiment of the invention shown in Figures 4-7 inclusive for with the examples shown in Figures 1 and 2 it is necessary to unite the converged supporting legs to produce the best result.

Various modifications may be made in carrying out the details of the invention hereinbefore described or in the application thereof, and it is to be understood that any modification coming fairly within the terms of the appended claims shall be covered thereby.

I claim:

1. A display device comprising a body with supporting legs at each side thereof, said legs 100 being connected to said body on angularly disposed crease lines whereon said legs are folded so as to converge and bring the free ends thereof together vertically to form a set easel support for said body, said legs having means comprising oppositely disposed notches one adjacent to the extremity of each leg and said notches interlocking so as to retain said legs in the operative position.

2. A display device comprising a body with 110 supporting legs at each side thereof, said legs being connected to said body on angularly disposed crease lines whereon said legs are folded so as to converge and bring the ends of said legs together to form a set easel support for 115 said body, said legs having means adjacent to the extremities thereof interlocking so as to retain said legs in the operative position, and said means comprising a series of notches whereby adjustability is obtained.

3. A display device comprising a show card and an easel integral therewith, said easel being composed of side pieces folding on diagonally disposed crease lines whereon said pieces are foldable so as to converge to form a support for said show card in an angular position and said show card having a cut out portion adapted to be folded so as to be displaced relatively to said show card as a platform to support a piece of merchandise.
